UNITED STATES PATENT OFFICE

CHARLES LAURENCE BURDICK, OF LONDON, ENGLAND

PAPER FOLDING MACHINE

Application filed July 22, 1929, Serial No. 380,218, and in Great Britain September 24, 1928.

This invention relates to paper folding machines.

In my British patent specification No. 178,531, I have described such a machine in which a sheet is fed between substantially parallel articulated plates which are then folded, a member preferably withdrawing the sheet and giving it an additional fold by passing between two sets of such plates, bars or posts being provided to complete the fold.

The present invention relates generally to such a machine and comprises improvements adapted but not necessarily confined thereto.

In order to make the nature of the invention understood and for ease of description it is proposed to describe the improved features or combinations with reference to the machine described in my aforesaid patent.

A machine made in accordance with the present invention embodies sheet feeding means, plate folding means and blade operating means, the whole being combined with a single operating cylinder or like revolving member arranged longitudinally of the machine and provided with cam paths whereby the movements of the several parts are effected and co-ordinated. The invention comprises the above combination and further includes the novel features, combinations and arrangements which are embodied in the apparatus now to be described and are specifically claimed.

Referring now to the accompanying drawings,

Figure 1 is a side elevation of the machine, Figure 2 an end elevation, and

Figure 3 a plan view.

Figure 4 is a perspective view to an enlarged scale showing the feed of a magazine.

Figure 5 shows the magazine also to an enlarged scale, and

Figures 6 and 7 are detail views making clearer the operation of certain parts.

Figure 8 is a side elevation of the machine with parts in section and parts broken away to illustrate more particularly the correlation of the parts.

In the preferred form as shown upon the drawings, the operations of the machine are all derived from a cylinder 1 operated

through gear wheels 2 and 3 by means of a belt pulley 4 or cranked handle or handwheel 5. The cylinder is provided with cam paths, the front path 6 operating a feed device by means of a downwardly projecting pin 7 carried on a downward projection 8 from the feed slide 9 running upon rails 10 disposed near the upper portion of the centre of the machine. The slide 9 carries a gripper 11 normally spring-pressed by a spring 12 against an anvil 13 carried by the slide. The slide is shown in all figures in its front position—that is to say when it is nearest to the feeding end of the machine. As indicated at Figure 7 a spring trigger 14 has just been tripped by a fixed pin 15 to release the gripper 11 which will just have seized the front edge of the next sheet to be folded, between itself and the anvil 13. In the extreme forward position of the feeding slide the gripper 11 is opened by contact of the stud 16 against the inclined abutment 17 whereby the end of the trigger 14 is caught under the abutment 11a of the gripper and the gripper releases the sheet and remains open until it returns to grip the next sheet upon release of the trigger.

A central cam path 18 is engaged by a pin 19 depending from the folding slide 20. The latter runs upon rollers 21, 21 engaging in lateral slideways 22 running longitudinally of the edges of the machine. Uprights 23 carry links 24 each of which is coupled to one of the foremost of the sliding stub spindles 25, 25 . . . sliding in the longitudinal slots 26 and supporting the folding plates.

A rear cam path 27 engages a pin 28 depending from the slide 29. A roller 30 carried by this slide runs in a slot 31 formed in a secondary slide 32 to which the blade 33 is pivoted at 34. This slot arrangement acts as a lost motion device so that upon initial movement of the slide 29 the roller 30 raises the blade 33 to the upright position shown in the drawings. At the same time the posts 51, 51a with their supporting brackets 53 are raised to the upright position shown by the passage beneath them of the forward projections 64 carried at the front of the slide 29, and are held raised by the passage

of a secondary slide 32 beneath them during further movement of the primary slide. During this movement the secondary slide 32 is carried bodily backward with the blade upright until it reaches the position in the drawings.

A magazine of clips 35 indicated at Figure 5 is arranged to fit into slot 36. At the back of each clip 35 is formed a slot 37, forming a rack adapted to be engaged by the teeth of a gear wheel 38 mounted upon the same vertical spindle 39 as a ratchet wheel 40. The magazine of clips 35 is adapted to be fed by means of the pawl 41 to bring successive clips into position to be entered by the blade 33. This pawl 41 is springpressed by spring 42 to engage the teeth of the ratchet wheel 40. The ratchet device is operated by a forward stroke of a projecting abutment 44 carried by a feed bar 45 which is reciprocated in the longitudinal direction of the machine by means of a bell crank 46 having a fixed fulcrum at 47 and provided with an engagement 48 between collars on the bar 45 and at the other end with a stud 49 engaging an inclined cam slot 50 carried by a feed slide 9. Normally, (when there is no note or other paper in the folding mechanism) the abutment 44 fails to contact with the lever 43 as may be seen at Figure 4. When a folded note is carried by the blade 33 between the posts 51, 51a to produce the final fold there is a certain amount of spring. The post 51 in its vertical position comes against a rigid backing bracket 52 and in consequence the slide spring moves the post 51a and its supporting bracket 53 sufficiently to depress the lever 54. This imparts a partial rotation to the rod 45 by pressure upon the arm or plate 55 and elevates the abutment 44 sufficiently to cause it to engage with the lever 43 and to impart a stroke to the pawl 41 so rotating the ratchet wheel 40 to the extent of one tooth and bringing the next clip 35 into position.

On the forward stroke of the rod 45 after partial rotation as described above a projecting arm 56 lifts an inclined deflector plate 57 about its pivot 58 but on the return stroke the arm 56 engages the upper surface of the plate 57 thus rotating the rod 45 back to its initial or inoperative position ready to be reset as soon as another note is passed between the posts.

The pairs of articulated plates 60, 60 between which the flat note is drawn by the slide 9 are arranged in two sets one upon each side of the machine as may be seen at Figure 3. The gap between the two sets of plates is bridged by raised bars 61, 62, and it is found that the presence of these bars sufficiently coordinates the folding action of the two sets which accordingly do not require to be connected by a lazy tongs mechanism as I have previously proposed.

The sheet reservoir 63 may conveniently

be arranged to be widened or narrowed to suit sheets of different widths—for example notes of a different value; for this purpose it may be formed of two longitudinally divided portions connected by two or more pairs of pivoted links and provided with stops or abutments to hold it at the desired setting, or the width may be set by means of an adjusting screw 65 as shown at Figure 3.

The operation of the machine can now be followed. The notes having been placed in the reservoir with the bottom one furthest back the handle 5 is rotated until the gripper 11 engages the bottom note. As soon as the plates 60 are flat the feed motion of the gripper between them is started by means of the forward cam. Having reached its extreme backward position the note is released from the gripper and the return stroke takes place. Upon completion of the return stroke the central cam causes the notes to be folded and just before they are completely folded the posts 51 and 51a and the blade 33 become upright. Further motion moves the secondary slide and the blade carries the note through the posts (thus setting the magazine feed device) and into a clip 35. The further rotation causes the lowering of the blade and posts and straightening of the plates ready to receive the next note already seized by the gripper 11.

I claim:—

1. A paper folding machine including sets of folding plates, means for feeding a sheet between two sets of said plates, means for actuating the said plates relatively to one another to fold the sheet, means for withdrawing the folded sheet from the said plates, a rotary driving member, revolving cam paths operated by said driving member, and operative connections whereby the said cam paths effect and coordinate the movements of the said sheet feeding, plate actuating and sheet withdrawing means.

2. A paper folding machine including a pair of parallel articulated plates, means including a slide for feeding a sheet between said plates, means including a slide for folding the plates with the sheet between them, means including a slide for withdrawing the folded sheet from the folded plates, a revolvable cam path controlling each of said slides and means to cause said cam paths to revolve in a predetermined timed relationship.

3. A paper folding machine comprising two sets of parallel articulated plates arranged with a gap between them, a paper-feeding device running along said gap to carry a paper into position between the parallel plates of both sets, a blade passing through said gap to withdraw the folded paper and members bridging the gap but out of the path of said feeding device and said blade.

4. In a paper folding machine, a folding

mechanism comprising two sets of parallel articulated plates arranged so that a paper in position for folding extends with a gap between them, stub-axles projecting outwardly
5 from plates of each set, slideways along which said axles are movable for folding the plates, and connections bridging said gap but out of the area required by the paper and coordinating the movements of the plates of the
10 two sets.

5. A paper-folding machine comprising paper-folding plates, paper-feeding means to feed the paper to said plates, plate-actuating means, paper-withdrawing means, and a revolving member arranged longitudinally of the machine and carrying cam paths whereby the plate-actuating means and the paper-withdrawing means are operated.

6. A paper-folding machine comprising paper-folding plates, paper-feeding means to feed the paper to said plates, plate-actuating means, paper-withdrawing means, and a revolving member arranged longitudinally of the machine and carrying cam paths whereby the paper-feeding means, the plate-actuating means and the paper-withdrawing means are operated.

7. A sheet-folding machine including a folded sheet receiving magazine, means to feed the magazine into position to receive successive sheets, and means whereby the said feeding means are made operative by the actual presence of a folded sheet in the machine ready to be fed to the magazine.

35 8. In a sheet-folding machine, spaced members to receive a folded sheet, means to feed the folded sheet between said spaced members, and mechanism operated in the relative movement of the spaced members incident to the passage of the folded sheet between them for compelling operation of an incidental part of the folding machine.

40 9. A sheet-folding machine including spaced members to receive a folded sheet between them, means to feed the folded sheet between said spaced members and thereby impart relative movement to said members, and feed mechanism for an incidental part of the folding machine operated in the relative movement between said spaced members.

In testimony whereof I affix my signature.
CHARLES LAURENCE BURDICK.
